UNITED STATES PATENT OFFICE

2,375,454

DECK

Ernest M. Wichert, Wilkinsburg, Pa.

Application January 26, 1943, Serial No. 473,586

10 Claims. (Cl. 94—11)

The purpose of this invention is the creation of a strong, continuous deck made of light, portable panels to provide paved areas for airplane runways, vehicular traffic, storage, handling of materials, etc.

Advantages of the invention are:

(1) Several times greater strength of deck than with prevailing type, and with greater economy and simplicity of fabricating, assembling and dismantling.

(2) Continuity in all directions without resorting to welding, overlapping, riveting, or the like.

(3) Vital material and labor are conserved.

(4) Shipping weight and space are conserved.

(5) The portable panels are very light in weight for the area covered, yet are of unprecedented great strength.

Other details, objects and advantages of the invention will become apparent as the following description of certain present preferred embodiments thereof proceeds.

In the accompanying drawings I have shown certain present preferred embodiments of the invention, in which:

Figure 1 is a fragmentary plan view of portions of four adjacent panels of a portable deck as laid in spaced apart relation prior to being connected together;

Figure 2 is a vertical cross-sectional view taken on the line II—II of Figure 1;

Figure 3 is a fragmentary perspective view to enlarged scale of a portion of one of the deck panels shown in Figure 1 to clarify structural details thereof;

Figure 4 is a fragmentary plan view of a portion of the structure shown in Figure 1 but to enlarged scale with a connecting device for connecting together adjacent panels of the deck shown in place, the wedge of the connecting device being omitted for clarity;

Figure 5 is a vertical cross-sectional view taken on the line V—V of Figure 4;

Figure 6 is a vertical cross-sectional view taken on the line VI—VI of Figure 4, the wedge omitted in Figures 4 and 5 being shown in place;

Figure 7 is a fragmentary diagrammatic plan view of a blank adapted to be die-formed into one of the panels shown in Figures 1 to 6, inclusive, prior to the final die-forming step;

Figure 8 is a perspective view of one element of the connecting device shown in Figures 4, 5 and 6;

Figure 9 is a perspective view of another element of such connecting device;

Figure 10 is a perspective view of a wedge used

for forcing the elements shown in Figures 8 and 9 into cooperative position to connect panels of the deck; and

Figure 11 is a vertical cross-sectional view through a modified form of structure employing a different form of connecting device.

Figure 1 shows portions of four fabricated panels 2 laid on the ground adjacent to each other. In this (recommended) case each panel is made of a No. 12 gauge sheet of steel 2 ft. wide x 8 ft. long. When fabricated one panel measures 1 ft. 11 in. x 7 ft. 11 in. and weighs 67 pounds. The panels may also be made out of other materials. These panels are laid on the ground with 1 in. space between adjacent panels. The panels are now ready to be made into a continuous deck by fixedly connecting them with the connecting devices as shown in Figures 4 to 6, inclusive, and 8 to 11, inclusive. The panels are symmetrical about both longitudinal and transverse axes so that either end of one panel may be connected with either end of another panel and either side of one panel may be connected with either side of another panel, thus making the laying fool-proof. The connecting devices are now laid over opposed connecting points, engaging the four tapered holes 3 at each connecting point. While doing this the center locking portion of the connecting device as shown in Figure 9 is turned so that its lower head 4 will be lengthwise with the 1 in. wide space formed between the adjacent panels. As this head is only $\frac{1}{8}$ in. wide, it can easily enter the 1 in. space between panels until the head is below the flanges 5 of the two adjacent panels. The locking portion is then turned 90° and, in the form of connecting device shown in Figures 8, 9 and 10, the key 6 is inserted and driven tight with any ordinary hammer. If it is desired to remove and replace any one panel from the assembled runway or deck, the operation above described is reversed and the panel is simply lifted out from between adjacent panels and another panel inserted.

Figure 7 shows a portion of a metallic sheet 2'-0" wide and 8'-0" long with slits 7 and 8 cut or punched in the sheet and a V 9 cut out of each corner. This drawing shows the condition of the sheet after the first operation.

The sheet is then placed between two sets of dies in a press in which flanges 5 are formed along all four edges and flanges 10 in staggered arrangement are simultaneously formed throughout the sheet. The location of these flanges is shown in dotted lines in Figure 7 and in full lines in Figure 1. The forming of all these

flanges and their staggered relation to one another increases the moment of inertia of the panel several times over that possessed by the flat sheet. Figure 4 shows all flanges pitched at an angle of 2 vertical to 1 horizontal (about 60°) with respect to the sheet's surface. This is for two good reasons. First, it enables the panels to be nested, thus requiring minimum shipping space. Second, when loads are applied to the deck the flange structure tends to compact the ground, thus increasing the bearing capacity.

It will be observed that the forming of the interior groups of flanges 10 produces oblong holes 11, and since the edge flanges 5 of adjacent panels are spaced 1 inch apart they form a groove interrupted every 8 inches by a connecting device, thus forming rows of oblong holes. All these holes or slots provide an efficient non-skid deck. They further allow vegetation to grow through the deck when desired for military camouflage; also these holes facilitate handling, placing and dismantling of panels.

Referring to Figure 7, it will be noted that there are pairs of slots 7 near the edges of the panel and at right angles to the edges. The metal between the slots of each of such pairs of slots is pressed into a strap 12 about 1 1/4 inches wide and shaped as shown in plan in Figure 4 and in cross section in Figure 5. These straps are formed simultaneously with the forming of the flanges and of the tapered round holes 3 at opposite sides of the straps. Thus it will be apparent that the manufacture of the panels requires only two operations; first, punching of slots, sub-punching of small round holes for receiving connecting units and V's at corners, all as shown in Figure 7; second, pressing into shape flanges, connector straps and tapered round holes for connecting devices, all as shown in Figures 1, 2 and 3. The moment of inertia of each panel at all sections perpendicular to the plane of the panel and of a length in the plane of the panel equal to the smallest dimension of the panel in its plane is substantially the same. Figures 8, 9 and 10, on the one hand, and Figure 11, on the other hand, show two different types of connecting devices as above described. Either type engages and fixedly connects two adjacent panels at intervals of about 8 inches. Each connecting device together with the straps formed in the adjacent panels near the edges thereof forms a structure having resisting moments slightly greater than the panel, thus assuring that the moment of inertia of the deck at all sections perpendicular to the plane of the deck and of a length in the plane of the deck equal to the smallest dimension of the deck in its plane is substantially the same.

The form of connecting device shown in Figures 4, 5, 6, 8, 9, and 10 is in three pieces shown, respectively, in Figures 8, 9 and 10. The piece shown in Figure 9 I term the bottom and consists of a lower head or base 4 adapted to be positioned in use with its under surface resting upon the ground, such piece or bottom having opposed lower clamping jaws 15 and an upwardly projecting central post 16 surmounted by a cap 17. The post is slotted as shown at 18. The piece shown in Figure 8 is of generally spider form having a base 19 provided with a central opening 20 to receive the post 16. The base 19 is provided with slots 21 and 22 in its upper surface, such slots being disposed opposite each other and forming in effect a continuous transverse slot intersecting the opening 20 and tapered from a

relatively shallow depth at the outside of the slot 21 to a relatively great depth at the outside of the slot 22. The slots 21 and 22 are of approximately the same width as the slot 18. Connected with the base 19 of the spider are upper clamping jaws 23 adapted to cooperate with the jaws 15 as will presently appear. Frame members 24 also connected with the base 19 carry cross members 25 each having at each end upon its under surface a downwardly projecting tapered pin or stud 26.

The pieces of the connecting device shown in Figures 8 and 9 and which have just been described are preferably loosely but permanently connected together in the shop. Before the cap 17 is applied to the post 16 the post is passed upwardly through the opening 20. Then the cap 17 is applied, which may be done either by swaging or forging the upper end of the post to form the cap analogous to riveting or by welding or otherwise attaching a separate piece to the upper end of the post. In any event, the two parts of the connecting device are preferably permanently connected together before leaving the shop so that they can never become separated. However, the vertical distance between the top of the base 4 and the under surface of the cap 17 of the bottom is considerably greater than the vertical dimension of the base 19 of the spider so that the two members of the connecting device may move freely relatively to one another.

When the connecting device is in place the jaws 15 underlie the seats 27 of adjacent sections and the jaws 23 overlie such seats as clearly shown in Figure 5. However, the dimension of the base 4 at right angles to the dimension between the jaws 15 is less than the width of the space between sections. Consequently when the connecting device is applied the spider is set down with the pins 26 in the holes 3 of the two opposed pairs of such holes in adjacent sections as shown in Figures 4, 5 and 6 and the base 4 is initially oriented with its longitudinal dimension, i. e., its dimension between the jaws 15, parallel to the slot or opening between sections. After the base 4 has passed downwardly between adjacent sections it is turned about the axis of the post 16 through an angle of 90° until the jaws 15 underlie the opposed seats 27. Thereupon the key or wedge 6 (Figure 10) is driven through the slots 18, 21 and 22, bearing against the under side of the cap 17 and against the bottoms of the slots 21 and 22 to force the spider relatively downwardly and the bottom relatively upwardly and thus draw the respective pairs of jaws 15 and 23 together to tightly clamp adjacent sections. At the same time the tapered pins 26 are drawn down tightly into the holes 3, thus forming firm connections between each section and the connecting device, which connections are spaced substantially apart in a direction at an angle to the plane of the section.

The connecting device shown in Figure 11 functions similarly to that shown in Figures 4, 5, 6, 8, 9 and 10 except that the post 16' in Figure 11 instead of being capped is threaded as shown at 28 to receive a nut 29. When the connecting device is to be applied the nut 29 is backed off on the post 16' so that the bottom member of the connecting device is loose relatively to the spider and after the parts have been positioned relatively to the sections to be connected together as above described the nut 29 is drawn up to force the clamping jaws together, its function being in all respects identical to the function

of the wedge 6 in the first described form. In each case inclined plane means is employed for drawing the clamping jaws together, the wedge and the threaded nut both being inclined plane means.

A further advantage of this type of deck, with its flanged openings in staggered arrangement and the flanges buried in the ground, is the fact that expansion and contraction due to temperature changes produce only negligible stresses even when deckings or runways are built continuous for over one mile.

The connecting devices may be made of malleable iron, or cast or pressed steel. Each unit, if of steel, weighs 0.9 pound.

A great advantage of the invention is that, as the deck is several times as strong as conventional decks, the chances of having to replace damaged panels are several times less, and in the event of a damaged panel having to be replaced it can be done very speedily as there is no chance that the connectors cannot be readily disengaged, there being comparatively few connections and each acting independently, not in series of several dozen, as is the case in some conventional decks where all the connecting lugs must first be straightened and aligned before any damaged panel can be removed.

An important advantage is that not only is my improved panel several times as strong as a conventional panel but at the same time one of my improved panels, although requiring only 72 pounds of steel for its manufacture, covers 16 square feet of deck area, while a conventional panel, which requires 92 pounds of steel for its manufacture, covers only 12.5 square feet of deck area. Thus there are required to be handled 28% less number of panels of my improved deck to assemble or dismantle a given area of decking. This feature seems very important in case hurried dismantling of deckings or repair thereof becomes necessary.

While I have shown and described certain present preferred embodiments of the invention it is to be distinctly understood that the invention is not limited thereto but may be otherwise variously embodied within the scope of the following claims.

I claim:

1. A deck panel comprising a sheet having at its peripheral edges flanges extending at an acute angle to the plane of the panel, said flanges having portions deformed to extend at a smaller acute angle to the plane of the panel to provide depressions for receiving connecting means to connect the panel with adjacent panels.

2. A deck panel comprising a sheet having at its peripheral edges flanges extending at an acute angle to the plane of the panel, said flanges having portions depressed so as to extend at a smaller acute angle to the plane of the panel and partially severed from adjacent portions to form seats for connectors for connecting the panel with adjacent panels.

3. A deck panel having therein elongated openings each completely surrounded by a flange, the openings being arranged in a pattern so as to form sets of generally parallel rows of openings, the rows of each set extending generally at right angles to those of the other set, each opening in a row having its major axis oriented substantially at right angles to the major axis of each adjacent opening in the same row and substantially at right angles to the major axis of the nearest opening in each adjacent row generally

parallel to the first mentioned row, openings in adjacent generally parallel rows of each set and which openings have their major axes extending transversely of the extent of said rows overlapping in the direction of extent of said rows.

4. A generally rectangular deck panel having flange means at at least certain of its peripheral edges, the panel having therein elongated openings each completely surrounded by a flange, the openings being arranged in a pattern so as to form sets of generally parallel rows of openings, the rows of each set extending generally at right angles to those of the other set, each opening in a row having its major axis oriented substantially at right angles to the major axis of each adjacent opening in the same row and substantially at right angles to the major axis of the nearest opening in each adjacent row generally parallel to the first mentioned row, openings in adjacent generally parallel rows of each set and which openings have their major axes extending transversely of the extent of said rows overlapping in the direction of extent of said rows.

5. A deck panel having a peripheral flange thereabout, the panel having therein elongated openings each completely surrounded by a flange, the openings being arranged in a pattern so as to form sets of generally parallel rows of openings, the rows of each set extending generally at right angles to those of the other set, each opening in a row having its major axis oriented substantially at right angles to the major axis of each adjacent opening in the same row and substantially at right angles to the major axis of the nearest opening in each adjacent row generally parallel to the first mentioned row, openings in adjacent generally parallel rows of each set and which openings have their major axes extending transversely of the extent of said rows overlapping in the direction of extent of said rows.

6. A generally rectangular deck panel having therein elongated openings each completely surrounded by a flange, the openings being arranged in a pattern so as to form sets of generally parallel rows of openings extending generally parallel to the edges of the panel, the rows of each set extending generally at right angles to those of the other set, each opening in a row having its major axis oriented substantially at right angles to the major axis of each adjacent opening in the same row and substantially at right angles to the major axis of the nearest opening in each adjacent row generally parallel to the first mentioned row, openings in adjacent generally parallel rows of each set and which openings have their major axes extending transversely of the extent of said rows overlapping in the direction of extent of said rows.

7. A deck panel having therein elongated openings each completely surrounded by a flange, the openings being arranged in a pattern so as to form sets of generally parallel rows of openings, the rows of each set extending generally at right angles to those of the other set, each opening in a row having its major axis oriented substantially at right angles to the major axis of each adjacent opening in the same row and substantially at right angles to the major axis of the nearest opening in each adjacent row generally parallel to the first mentioned row, openings in adjacent generally parallel rows of each set and which openings have their major axes extending transversely of the extent of said rows overlapping in the direction of extent of said rows, the flanges surrounding the openings being relatively deep

along the longitudinal edges thereof and relatively shallow at the ends thereof.

8. A deck panel having therein elongated openings each completely surrounded by a flange, the openings being arranged in a pattern so as to form sets of generally parallel rows of openings, the rows of each set extending generally at right angles to those of the other set, each opening in a row having its major axis oriented substantially at right angles to the major axis of each adjacent opening in the same row and substantially at right angles to the major axis of the nearest opening in each adjacent row generally parallel to the first mentioned row, openings in adjacent generally parallel rows of each set and which openings have their major axes extending transversely of the extent of said rows overlapping in the direction of extent of said rows, the flanges being inclined to the general plane of the panel at an angle such that the panel is rendered nestable with identical panels.

9. A deck panel having a peripheral flange and having therein elongated openings each completely surrounded by a flange, the openings being arranged in a pattern so as to form sets of generally parallel rows of openings, the rows of each set extending generally at right angles to those of the other set, each opening in a row having its major axis oriented substantially at right angles to the major axis of each adjacent open-

ing in the same row and substantially at right angles to the major axis of the nearest opening in each adjacent row generally parallel to the first mentioned row, openings in adjacent generally parallel rows of each set and which openings have their major axes extending transversely of the extent of said rows overlapping in the direction of extent of said rows, the flanges being inclined to the general plane of the panel

10 at an angle such that the panel is rendered nestable with identical panels.

10. A composite deck comprising panels laid in generally coplanar relation and fastened together, the deck having therein elongated openings each completely surrounded by a flange, the openings being arranged in a pattern so as to form sets of generally parallel rows of openings, the rows of each set extending generally at right angles to those of the other set, each opening in a row having its major axis oriented substantially at right angles to the major axis of each adjacent opening in the same row and substantially at right angles to the major axis of the nearest opening in each adjacent row generally parallel to the first mentioned row, openings in adjacent generally parallel rows of each set and which openings have their major axes extending transversely of the extent of said rows overlapping in the direction of extent of said rows.
